ICE TONGS

Harold W. McKenzie, Beaverton, Oreg., assignor to
Thompson Metal Fab, a corporation of Oregon

Filed June 10, 1965, Ser. No. 85,653

Term of patent 14 years

(Cl. D54—13)

FIG. 1 is a side elevational view of my ice tongs in closed position;

FIG. 2 is an edge view of my ice tongs taken in the direction of arrow 2—2 of FIG. 1;

FIG. 3 is a sectional view of my ice tongs taken along line 3—3 of FIG. 2, showing the tongs partly opened; and

FIG. 4 is a side elevational view of my ice tongs in fully opened position, the view being taken from the side opposite to that shown in FIG. 1.

I claim:

The ornamental design for ice tongs, as shown and described.
